(57) **CLAIM**

The ornamental design for a lumbar-sacral interbody spacer implant, as shown and described.

DESCRIPTION

FIG. 1 is a top perspective view of the lumbar-sacral interbody spacer implant comprising the new design, showing the center hole and connector hole in phantom;

FIG. 2 is a side perspective view of the design of FIG. 1 showing the center hole and connector hole in phantom;

FIG. 3 is a top view of the design of FIG. 1 showing the center hole and peripheral holes in phantom;

FIG. 4 is a bottom view of the design of FIG. 1 showing the center hole and peripheral holes in phantom;

FIG. 5 is left side elevational view of the design of FIG. 1, where the right side elevational view is a mirror image;

FIG. 6 is a back elevational view of the design of FIG. 1; and, FIG. 7 is a front elevational view of the design of FIG. 1 showing the connector hole in phantom.

The broken lines in the figures are for illustrative purposes only and form no part of the claimed invention.
